(57) **CLAIM**

I claim the ornamental design for a hand-shaped desk organizer, as shown and described.

DESCRIPTION

FIG. 1 is a perspective view of a hand-shaped desk organizer, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken lines just in inside in FIGS. 1 and 7, which define the bounds of the claimed design, form no part thereof. The circular broken line central to the boundary line in FIG. 7 illustrates environmental matter, and forms no part of the claimed design.
